Specification for Design.

Patented Aug. 14, 1917.

Application filed June 4, 1917. Serial No. 172,824. Term of patent 7 years.

To all whom it may concern:

Be it known that I, WILLIAM R. UHLEMANN, a citizen of the United States of America, residing at Chicago, in the county of Cook and State of Illinois, have invented a new, ornamental, and original Design for Lens-Cabinets, of which the following is a specification, reference being had to the ac-

companying drawing, forming a part thereof, and which represents a perspective view of a lens cabinet illustrating my new design.

I claim:

The ornamental design for a lens cabinet, as shown.

WILLIAM R. UHLEMANN.
